Pierce, P.L.C.

(57) **CLAIM**

The ornamental design for an electronic vaporizer, as shown and described.

DESCRIPTION

FIG. 1 is a perspective front view of an electronic vaporizer. FIG. 2 is a front view of the electronic vaporizer of FIG. 1. FIG. 3 is a rear view of the electronic vaporizer of FIG. 1. FIG. 4 is a right side view of the electronic vaporizer of FIG. 1. FIG. 5 is a left side view of the electronic vaporizer of FIG. 1. FIG. 6 is a top view of the electronic vaporizer FIG. 1; and, FIG. 7 is a bottom view of the electronic vaporizer of FIG. 1. The broken lines in the drawings depict portion of the electronic vaporizer that form no part of the claimed design.

1 Claim, 4 Drawing Sheets

Related U.S. Application Data

a continuation of application No. 29/572,791, filed on Jul. 29, 2016, now Pat. No. Des. 842,535.
